UNITED STATES PATENT OFFICE

2,433,104

AIR-CONDITIONING APPARATUS

Arthur H. Eberhart, Springfield, Mass., assignor
to Westinghouse Electric Corporation, East
Pittsburgh, Pa., a corporation of Pennsylvania

Application June 24, 1944, Serial No. 541,984

2 Claims. (Cl. 98—94)

1

My invention relates to an air conditioning unit of the type adapted to be mounted on the sill of a window, with one end of the unit facing the room and the other end thereof facing the outside atmosphere.

One object of my invention is to produce improved means for mounting an air conditioning unit in a window.

The type of window structure for which the present invention is particularly adapted, includes jambs and sash grooves formed by parallel, vertical, wooden strips secured to said jambs. Since the function of the groove-forming strips is merely to guide the sash of the window and to provide an overlap to keep out the weather, such strips are usually not very strongly constructed and, of course, are weakened with use and age.

It is, therefore, a further object of my invention to produce improved mounting means which will rigidly engage the air conditioning unit and portions of the opposite walls of the sash grooves substantially coextensively with the height of the unit. This serves to distribute the strain resulting from the tilting movement of the unit, and any shock or impact incidental to the installation of the unit in the window, over a large area so as to prevent damage to the sash groove strips and to guard against the possibility of such strips breaking and allowing the unit to fall out the window or into the room according to the direction in which the tilting moment is exerted.

A still further object of my invention is to produce an improved mounting for an air conditioning unit which coacts with the window structure to produce a satisfactory weather-proof joint between the unit and the window structure.

A still further object of my invention is to produce improved mounting means which will be adjustable for use in windows having openings or sash grooves of different sizes and which will be inexpensive to manufacture and easy to install.

These and other objects are effected by my invention as will be apparent from the following description and claims taken in connection with the accompanying drawing, forming a part of this application, in which:

Fig. 1 is a perspective view, looking from outside of the window, showing the improved mounting means embodying my invention;

Fig. 2 is a horizontal section through one of the jambs of the window, showing the mounting means engaging the sash grooves;

Fig. 3 is a section through the bottom sill of a window and the bottom of the air conditioning unit casing; and

2

Fig. 4 is a vertical section through the top of the air conditioning unit casing and a lower portion of the window sash resting thereon.

In Fig. 1 there is shown a casing 10 mounted on the sill 12 of a window having jambs 14 and a sash movable vertically in opposite sash grooves 18 formed in the jambs 14. The sash grooves 18 are formed by outer strips 20 and an intermediate strip 22 which are secured to, or are integral with, 10 the jambs 14 and which constitute opposite walls of said grooves.

The casing 10 may be that of a completely pre-assembled and self-contained, window-mounted air conditioning or ventilating unit, or it may be 15 in the nature of a shell forming part of the mounting means and into which preassembled air conditioning machinery may be inserted somewhat along the lines disclosed in Wolfert Patent No. 2,335,627.

20 When the casing 10 is placed on the window sill, a portion 24 thereof will extend into the room and the opposite portion 26 thereof will extend into the outside atmosphere. The casing 10 is formed of a top wall 28, a bottom wall 30 and 25 side walls 32, and may be secured to the sill 12 of the window by means of clamps, diagonal braces, or the like which do not form part of the invention and hence are neither shown nor described.

30 Due to the fact that the center of gravity of the casing 10, or of the air conditioning unit housed therein, may not coincide with the center of the window sill and, due to the fact that the window sill is usually narrow as compared with 35 the length of the casing, there usually is a tilting moment, which, if not resisted, will cause the unit to fall out the window, or into the room, depending upon the center of gravity of the unit.

In order to distribute the tilting moment over 40 as large a support surface as possible, I have devised improved mounting means which rigidly engage the casing 10 and a relatively large surface of the sash grooves 18. My improved mounting means are further adapted to engage the sash 45 grooves without the use of nails, screws or the like and are readily adjustable for use in connection with windows of different sizes and sash grooves of different widths.

The mounting means embodying my invention 50 includes U-shaped brackets, each of which comprises a vertically-extending bight portion 34 adapted to engage a corresponding portion of a sash groove in the adjacent jamb of the window, and upper and lower horizontally-disposed limbs 55 36 and 38 adapted to engage the top and bottom

walls of the casing 10. The upper and lower limbs 36 and 38, which will hereinafter be further referred to, include flat portions 40 and 41 and vertical flanges 42 and 44, respectively.

Each of the bight portions 34 is provided with horizontally-spaced, vertically-extending flanges 46 and 48 which are adapted to enter the sash grooves 18 and to abut against the opposite walls or strips 22 and 20 of the sash grooves. It will be noted that the flanges 46 and 48 extend substantially the entire height of the casing 10 so that they will engage corresponding portions of the strips 22 and 20, thereby distributing the strain caused by the tilting movement of the unit, or any impact incidental to the mounting of the unit, over a relatively large area of the groove-forming strips 22 and 20. In order to be able to adjust the flanges 46 and 48 to sash grooves of different widths, the flanges 46 and 48 are adjustably secured to the bight portions 34. As shown, the flanges 46 are fixed, and the flanges 48 are carried by strips 50 which are secured to the bight portion 34 by bolts or the like 52 engaging horizontal slots 54 in the bight portions 34. By loosening the bolts 52 and moving the strips 50, toward or away from the fixed flanges 46, the space between the flanges 48 and 46 may be varied according to the width of the groove 18 between the walls 20 and 22.

In order to accommodate window openings of different sizes, the U-shaped brackets are mounted for adjustment longitudinally of the casing 10 and of the window opening. This is accomplished by providing the horizontal limbs 36 and 38 of the U-shaped brackets with horizontal slots 56 extending longitudinally thereof and adapted to engage bolts or the like 58 which are fixed with respect to the casing 10. When it is desired to adjust the mounting means to fit a particular window opening, the bolts 58 engaging the slots 56 are loosened and the U-shaped brackets are moved toward or away from each other until they assume a position in which the bight portions 34 engage the sash grooves 18 in the opposite jambs 14 of the window. The bolts 58 are then tightened to retain the U-shaped brackets in the desired adjusted position. The lengths of the limbs 36 and 38, the length, number and spacing of the slots 56, the number and spacing of the bolts 58 and the length of the casing 10 are such that the limbs 36 and 38 will, throughout their entire range of adjustment, be secured to the casing 10 by two bolts 58 engaging each of the limbs 36 and 38. This prevents pivoting of the U-shaped brackets with respect to the casing.

To be adjustable as above described, the total length of the oppositely-disposed U-shaped brackets is less than the width of the average window opening so that a gap is left between the juxtaposed inner ends 60 of the upper and lower horizontal limbs 36 and 38 of the U-shaped brackets. Also, the length of the casing 10 is such that the gap referred to is always less than the width of the casing. In order to close this gap, I provide the top and bottom walls 28 and 30 of the casing with oppositely-facing upper and lower channel members which coat with the flanges 42 and 44 of the limbs 36 and 38 to close said gap.

Each of the upper channel members includes a flat portion 62, a vertical, relatively high flange 64 on the room side thereof and a relatively low vertical flange 66 on the opposite or outside side thereof. The flat portions 62 and the flanges 64 and 66 form a trough for receiving and guiding

the upper limbs 36 of the U-shaped bracket members, as shown in Fig. 4. Similarly, each of the lower channel members includes a flat portion 68, a vertical relatively high flange 70 on the room side thereof and a vertical relatively low flange 72 on the opposite or outside side thereof. The flat portion 68 and the flanges 70 and 72 provide an inverted trough for receiving and guiding the lower horizontal limbs 38 of the U-shaped brackets. The upper and lower channel members are preferably coextensive with the length of the casing and the flat portions 62 and 68 thereof are suitably secured in a substantially airtight manner to the top and bottom walls of the casing as by spot welding or the like.

When assembled as shown in Fig. 1, the flanges 42 and 44 of the upper and lower horizontal limbs 36 and 38 abut against the flanges 64 and 70 of the channel members and the gap between the ends 60 of the upper and lower limbs 36 and 38 is at all times closed by the flanges 64 and 70. The bolts 58 which engage the slots 56 in the flat portions 40 and 41 of the limbs 36 and 38 pass through and engage the top and bottom walls of the casing 10. As shown in Fig. 4, the channel members are made of relatively thin sheet metal, but the U-shaped brackets, which must resist the tilting moment, are made of heavy stock possessing sufficient rigidity.

In order to close such spaces as may be left between the opposite side walls 32 of the casing and the adjacent window jambs 14, I use filler pieces 74 which are secured by bolts or the like 76 to flanges 78 carried by or formed integrally with strips 80 secured to the side walls 32 of the casing in a substantially airtight manner. The marginal portions of the filler pieces 74 remote from the side walls of the casing are clamped in position between the fixed flanges 46 of the bight portions 34 and the adjacent walls or strips 20 of the sash grooves 18, as shown in Fig. 2. The filler pieces 74 are of the same thickness as the flanges 64 and 70 against which they abut as at 82.

As will be seen from Fig. 3, the flanges 70 of the bottom channel members and the flanges 44 of the lower horizontal limbs 38 abut against a ledge or riser 84 which usually forms part of the sill of the window structure illustrated.

In order to provide a substantially airtight junction between the top of the casing 10 and the bottom edge of the window sash 16, a gasket 86, extending the entire length of the window opening including the depth of the opposite sash grooves 18, is employed. The upper portion of the gasket is recessed longitudinally to form a shoulder or a seat 88 for the bottom edge of the sash. When the sash rests on the seat 88, it abuts against and overlaps the upper portion of the gasket as shown in Figs. 1 and 4. The gasket is provided with an internal vertical groove having a relatively wide lower portion 92 and a relatively narrow upper portion 94. The lower portion 92 of the groove is wide enough to engage the flanges 42 of the upper limbs 36 and the abutting portions of the flange 64 and filler pieces 74. The upper narrow portion 94 of the groove engages the portion of the flange 64 and the portions of the filler pieces 74 which extend above the top edges of the flanges 42, as clearly shown in Fig. 4. By this means the gasket is adequately supported along its entire length, including the portion thereof which coincides with the gap 75 between the ends 60 of the U-shaped brackets.

Assembly

The casing 10 to be mounted on the window sill 12 is equipped with the upper and lower channel members, the flat portions 62 and 68 of which are secured in an airtight manner to the top and bottom walls 28 and 30 of the casing. The U-shaped brackets are loosely secured to the casing 10, the casing 10 is placed on the window sill, and the U-shaped brackets are adjusted so that the flanges 46 and 48 thereof will extend into the opposite sash grooves 18 in the opposite window jambs 14. When the U-shaped brackets have been so adjusted, the bolts 58 are tightened rigidly to secure the U-shaped brackets to the casing. The filler pieces 74 are now cut to the proper width and, if necessary, to the proper height, and their outer marginal portions are seated in the sash grooves 18 between the flanges 46 and the strips or walls 20. The inner marginal portions of the filler pieces 74 are then secured by the bolts 76 to the flanges 78 of the strips 80 which are suitably secured to the side walls 32 of the housing in a substantially airtight manner. The strips 80 are now adjusted so as to cause the flanges 48 to abut against the strips or walls 22 of the grooves 18 and the bolts 52 are tightened. The gasket is then cut to size and fitted onto the flanges 42 and 64 and the upper portion of the filler pieces 74, and the sash 16 is lowered onto the seat 88 of the gasket. If it is found necessary further to counteract tilting moment of the unit, conventional angle braces engaging the unit and the window sill or the wall may be used.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. Means for mounting an air conditioning unit casing or other enclosure having vertical side walls and a horizontal top wall, in a window having jambs and a sash movable vertically in sash grooves formed in said jambs, said means comprising brackets including vertical portions adapted to engage said grooves and horizontal portions adapted to be secured to said top wall, vertical flanges carried by and coextensive with said horizontal portions, the total length of said horizontal portions being such that, when said vertical portions engage said grooves, a gap is left between the juxtaposed ends of said horizontal portions, a vertical flange carried by the top of said casing and abutting against the vertical flanges of said horizontal portions to close said gap, the vertical flange carried by the top of said casing being higher than the flanges carried by

said horizontal portions, and a gasket extending substantially the width of the window opening, said gasket having a lower relatively wide slot for engaging the abutting portions of said flanges and an upper relatively narrow slot adapted to engage the upper portion of the flange carried by said casing.

2. Means for mounting an air conditioning unit casing or other enclosure having vertical side walls and horizontal top wall, in a window having jambs and a sash movable vertically in sash grooves formed in said jambs, said means comprising brackets including vertical portions adapted to engage said grooves, horizontal portions adapted to be secured to said top wall and vertical flanges carried by said horizontal portions, the total length of said horizontal portions being such that, when said vertical portions engage said grooves, a gap is left between the juxtaposed ends of said horizontal portions, a vertical flange carried by the top of said casing and abutting against the vertical flanges of said horizontal portions to close said gap, said casing being smaller than the opening of said window whereby spaces are left between the vertical side walls of said casing and said jambs, filler pieces for closing said spaces, means for securing said filler pieces to the vertical side walls of said casing, said filler pieces being substantially of the same thickness as the flange carried by the top of said casing and having its upper edge substantially flush with the upper edge of said flange, the upper edge of the flange carried by the top of said casing and the upper edge of said filler pieces being higher than the upper edges of the abutting portions of the flanges carried by said horizontal portions, and a gasket extending substantially the width of the window opening, said gasket having a lower relatively wide slot for engaging the abutting portions of said flanges and an upper relatively narrow slot for engaging the upper edges of said filler pieces and the upper edge of the flange carried by the top of said casing.
